Atty.

UNITED STATES PATENT OFFICE.

SETH J. SPITLER, OF GREENVILLE, MICHIGAN.

CARPET-FASTENER.

SPECIFICATION forming part of Letters Patent No. 257,624, dated May 9, 1882.

Application filed March 15, 1882. (No model.)

To all whom it may concern:

Be it known that I, SETH J. SPITLER, of Greenville, in the county of Montcalm and State of Michigan, have invented new and useful Improvements in Devices for Laying Carpets; and I hereby declare that the following is a full, clear, and exact description thereof, reference being had to the accompanying drawings, which form a part of this specification.

10 The nature of this invention relates to certain new and novel improvements in the method and means employed for laying carpets, the object of the invention being to provide a device whereby the carpet can be laid without 15 the necessity of tacking the same to the floor; and the invention consists in the peculiar adaptation of a supplemental molding designed to be removably secured to the base of the mop-board, said supplemental molding being provided with suitable hooks to engage with the carpet, all as more fully hereinafter set forth.

Figure 1 is a perspective representing the application of my improved invention. Fig. 2 is a section showing the manner of securing 25 the carpet and molding in place.

In the accompanying drawings, A represents the mop-board of a room, and is a portion of the stationary carpentry in the ordinary construction of buildings. To this mop-board, near 30 the lower edge thereof, and at suitable distances apart, I rigidly secure the metallic loops or staples B.

C represents a strip of suitable molding, the back face of which is cut away its entire length, 35 substantially in the form shown. To the vertical rear face of this molding C, I rigidly secure the pins or lugs E, so that they shall be flush with such face of the molding. Near the lower edge of the molding, and upon the rear 40 face thereof, I secure a series of hooks, D, which are designed to engage with the edge of the carpet.

In practice the carpet, having first been fitted or cut so as to conform to the size of the room in which it is to be laid, is hooked upon 45 the series of hooks D, when one side and one end of the carpet may be secured to place by inserting studs E in their respective loops B upon the mop-board C. A proper stretcher is then applied upon the opposite side and end— 50 one at a time, of course—to draw the carpet to the side of the room, where it is detached. When it has been sufficiently stretched in this direction the studs E upon the respective strips of molding can readily be secured to the mop-board, as above described.

At the spaces occupied by the doors, and where the mop-board does not occur, the edge of the carpet may be provided with any suitable means for detachably securing the carpet 60 to the floor without the employment of tacks— as, for instance, a series of rings may be secured upon the lower edge of the carpet at these points to engage with suitable pins or stops, which project slightly above the floor 65 for the purpose. By this means it will readily be seen that the carpet can be quickly laid or taken up for the purposes of cleaning, or in cases of emergency, while the danger of ripping the carpet in taking it up when nailed to 70 the floor is entirely avoided.

What I claim as my invention is—

A device for securing or laying carpets, consisting of a supplemental molding, C, provided with studs E and hooks D, the latter of which 75 engage with the carpet, while the former engage with loops upon the base-board, substantially in the manner and for the purposes specified.

SETH J. SPITLER.
